UNITED STATES PATENT OFFICE.

ERNESTO EISENDECHER, OF VALDIVIA, CHILE.

WRIST-WATCH HOLDER.

1,338,563.

Specification of Letters Patent. Patented Apr. 27, 1920.

Application filed August 18, 1919. Serial No. 318,285.

To all whom it may concern:

Be it known that I, ERNESTO EISENDECHER, a citizen of the Republic of Chile, and a resident of the city of Valdivia, Chile, 5 have invented a new and Improved Wrist-Watch Holder, of which the following is a full, clear, and exact description.

This invention relates to improvements in wrist watch holders, an object of the 10 invention being to provide a device of the character stated, which when the wrist watch is in position thereon, will have the appearance of a clock and can be conveniently used as a desk clock or for display 15 purposes.

A further object is to provide a device 20 of the character stated which provides an elevated mounting for a wrist watch, and bracelet or strap thereon, and which provides a centering recess or pocket to accommodate the watch and hold it in proper 25 position relative to the support.

It is apparent that the device may be 30 variously ornamented and designed, lending 25 itself to artistic workmanship, but the function of a wrist watch support and improved mounting therefor, will be carried out in all designs so that the device in operation 35 will function and appear as a clock.

With these and other objects in view, the 30 invention consists in certain novel features of construction and combinations and arrangements of parts as will be more fully hereinafter described and pointed out in 35 the claim.

In the accompanying drawings:—

Figure 1 is a top plan view.

Fig. 2 is a view in front elevation.

1 represents a base, which may be of stone 40 composition, metal, wood, glass, or any other suitable material, and a plate 2 is secured on the base, and has standards 3 thereon.

The standards 3 may be of any desired

design, and support at their upper ends, a 45 horizontal form 4. This form may, if desired be covered with velvet, plush or other ornamental material 5 as shown, and is made at its upper edge with a recess 6 to provide a reduced portion to receive the 50 bracelet or strap 7 connected to a wrist watch 8. The ledge 9 formed by the recess 6 prevents downward movement of the strap or bracelet 7 and secures the watch against movement. 55

To further secure the watch and properly position the same centrally of the form 4, a recess or seat 10 is formed in the central portion of the front of the form 4 and as this recess 10 is made with inclined or tapering end walls, the watch supported therein 60 is held against downward as well as lateral movement.

While I have illustrated a bar 11, and bolts 12 for securing the form 5 to the standards, it is apparent this particular construction is not essential. 65

It is obvious that the device can be variously ornamented and designed to suit the 70 trade.

Various slight changes might be made in the general form of the parts described without departing from my invention, and hence I do not limit myself to the precise details set forth but consider myself at liberty to make such slight changes and alterations as fairly fall within the spirit and scope of the appended claim. 75

I claim:—

A wrist watch holder, comprising a base, 80 standards on the base, a wrist watch supporting form secured to the top of the standards and positioned substantially parallel to the base, said form having a groove around its upper edge forming a restricted 85 portion adapted to receive the strap or chain of a wrist watch.

ERNESTO EISENDECHER.
